UNITED STATES PATENT OFFICE.

ELIN K. NIELSEN, OF NEW YORK, N. Y.

COAT-STAND.

983,392.

Specification of Letters Patent. Patented Feb. 7, 1911.

Application filed April 21, 1910. Serial No. 556,796.

To all whom it may concern:

Be it known that I, ELIN K. NIELSEN, a subject of the King of Denmark, and a resident of the city, county, and State of New York, have invented certain new and useful Improvements in Coat-Stands, of which the following is a specification.

This invention relates to improvements in coat stands.

10 One object of the invention is to provide a coat stand adapted to be taken apart for transportation purposes.

Another object is to provide means for protecting the articles displayed or hung on 15 the stand.

Another object is to provide means for various adjustments when the stand is used for displaying goods in a store.

With these and other objects in view the 20 invention comprises a coat stand and accessories thereto as set forth in the following specification while the invention is illustrated in the accompanying drawing in which,

25 Figure 1 is a perspective view of a coat stand embodying the invention. Fig. 2 is a detail view of the means for taking the stand apart. Fig. 3 shows the stand taken apart, and Fig. 4 is a view somewhat diagrammatic showing how the stand may be used.

In the drawing the reference numeral 5 denotes a base provided with casters 6 and if desired a weight 7. On the top of the 35 base there is a boss 8 threaded on the inside for the reception of one of the upright sections 9 which is screwed into the said boss. As shown the upright consists of several sections 9, 9 and a section 10 of less length than 40 the section 9. Each section is provided at the one end with a socket 11 and at the other end with a stud 12 adapted to be screwed into the socket of the adjacent section as shown in Fig. 2 or into the internally 45 threaded boss 8 in the base 5. Thus the stand may be made up in various heights and this vertical adjustment is enhanced by having one or more sections of various lengths.

50 Display or supporting hook members 13 are provided. Each hook member comprises a collar 14 carrying one or more hooks 15 and adapted to be clamped to the

upright by wing bolts 16 so that the hooks may be set at various heights. 55

A shield or curtain support 17 is provided and preferably made of a strong wire formed into an oval loop which is suspended from arms 18 fast in a collar 19 which may be set on the upright and clamped by a bolt 60 16. Curtain rings 20 slide on the wire loop 17. On the top of the upright there may be fastened an ornamental knob if desired, or a hat support 21 may be screwed fast at the end of the uppermost section 10. 65

Fig. 4 suggests one way of using the stand. In this figure 22 represents a curtain suspended from the rings 20 for the protection of the garment hung on the stand. 23 is a hat resting on the hat support 21 and 24 represents garments such as ladies' waists hung on the hooks 15. 70

From the above it will be clear that the stand may be used in a home or in business. That the garments are protected against 75 dust by the curtain which latter can readily be drawn aside to display or get at the garments. Also the hat support furnishes a convenient rest for a hat. The stand may also be used to display millinery only, as it 80 may readily be made up into various heights to suit a show window display. As shown in Fig. 4 the hook members 13 may be set close together to increase the capacity of the stand. By using only double hook members 85 the capacity is doubled. The weight prevents the stand from upsetting and the same may easily be moved over the floor.

Fig. 3 shows the stand taken apart when it takes up but little space and may readily 90 be transported in a suit case.

It is thought that the above fully describes the invention and the advantages to be derived from its use, and as the construction may be varied within the description 95 here set forth I claim all such changes as come within the legitimate and intended scope of the claim.

I claim:—

A knock down garment stand comprising 100 a rectangular base, an upright detachably connected thereto and comprising a plurality of sections of various length, means integral with said sections for interconnecting and interchanging the said sections, said base being provided with a socket 105

for receiving the one end of any of said sections, hooks, means for securing the same at any point on the said upright, a curtain loop, means for securing the same 5 at any point on said upright, the length of said loop and of the longest of the said upright sections being substantially equal to the length of the said base for the

purpose of transportation when the stand is taken apart.

Signed at New York, N. Y. this 16th day of April 1910.

ELIN K. NIELSEN.
